UNITED STATES PATENT OFFICE.

JAMES LALLY, OF DES MOINES, IOWA, ASSIGNOR OF ONE-HALF TO
THOMAS G. ORWIG, OF SAME PLACE.

TRACE-BUCKLE.

SPECIFICATION forming part of Letters Patent No. 296,583, dated April 8, 1884.

Application filed July 31, 1882. (No model.)

To all whom it may concern:

Be it known that I, JAMES LALLY, of Des Moines, in the county of Polk and State of Iowa, have invented an Improved Trace-Buckle, of 5 which the following is a specification.

My invention is an improvement of the buckle patented November 30, 1880, No. 234,991; and it consists in a wedge formed integral with the frame of the sliding loop to clamp the trace 10 to the base-frame for the purpose of relieving the tongue from strain; in inclined planes on the side bars of the frame to cause the sliding loop and its wedge to rise relative to the cross-bar at the rear end of the frame, for the purpose of clamping the trace fast between the 15 wedge and cross-bar; in shaping the sliding frame and loop and the rear end of the base-frame in such a manner relative to each other that the combined loop and wedge can be 20 slipped in over the elevated cross-bar of the base-frame to slide upon the inclined planes of the side bars of the same frame, and also in such a manner that the two parts can be detachably connected without being liable to 25 separate when the trace is adjusted in the buckle or removed therefrom, all as herein-after fully set forth.

Figure 1 of my accompanying drawings is a top view, and Fig. 2 a perspective view, of 30 my improved buckle. Fig. 3 is a perspective view of the sliding loop and wedge. Fig. 4 is a longitudinal section, and Fig. 5 a perspective view of the buckle, a hame-tug, and a trace combined.

Jointly considered, these figures clearly illustrate the construction and operation of my 35 complete invention.

a represent the base-frame, in which *b* are the portions that form inclined planes relative to the cross-bar *c* at the rear end of the frame and the cross-bar *d* at the front end.

b' b' are upward bends in the frame extending from the inclined planes *b* of the side bars to the cross-bar *c* in such a manner as to 45 allow the sliding frame and loop to be moved in and out over the rear end of the frame whenever desired.

e is the top portion of the sliding frame. *e'* is a wedge formed integral therewith to 50 extend rearward therefrom.

f is a loop formed integral with the ends

and lower side of the top portion, *e*, and adapted in shape and size to allow the complete sliding frame to slip over the upwardly-bent rear end of the base-frame, and slide back and forth upon the inclined portions *b*, as required, to fasten or unfasten a trace in the buckle. 55

f' are the ends of the loop. They extend forward and downward at an angle relative to the loop portion *e* of the frame, to adapt the 60 complete frame and loop to be moved in and out over the rear end of the base-frame. (Dotted lines in Fig. 1 indicate that loops may be formed on the ends of the part *e*, as shown in the patent above referred to.) 65

h is a tongue projecting vertically from the center of the part *e*. This tongue may be left off when desired, and the trace clamped fast at any point desired by means of the wedge *e' e'*.

i i are lugs projecting vertically from the 70 ends of the part *e*, to serve as guards in keeping a trace straight and in line relative to the buckle and the draft applied to the trace.

Heretofore guards have been formed on a wedge adapted to slide between the side bars 75 of a buckle-frame, to keep the wedge in place on the trace; but my combination of guards with a wedge and a loop or frame that surrounds the buckle-frame and carries the wedge and guards on top of the side bars of the frame, to 80 aid in keeping the trace straight relative to the complete buckle, is new and advantageous.

In the practical use of my buckle, thus constructed complete in two parts, I fix a hame-tug to the front cross-bar, *d*, of the base-frame 85 and then slip the sliding frame, wedge, and loop forward over the rear end of the base-frame to rest upon the inclines *b*.

To connect a trace, I simply pass its front 90 end forward under the cross-bar *c* of the base-frame and over the top of the combined sliding frame and loop and allow the tongue to enter one of the perforations in the trace as I pass its front end into a loop or loops projecting outward from the hame-tug. As draft is 95 applied to the hame-tug and trace thus buckled together, the sliding frame and loop will move backward and upward on the inclines *b* of the base-frame and cause the wedge *e'* to press upward on the trace and clamp it fast against 100 the cross-bar *c*, as clearly shown in Fig. 4, to thereby relieve the tongue *h* from strain and

prevent short and damaging bends being formed in the trace.

By making the parts b' of the base-frame square relative to the frame, I can slip the 5 sliding frame and wedge over the front end of the base-frame and retain it permanently, as stated in my prior patent above referred to.

I claim as my invention—

1. In a buckle, the combination of a frame 10 having inclined planes b on its parallel side bars and upwardly or outwardly bent portions b' at the rear ends of said inclined planes, and a sliding detachable loop or frame, $e f f$, hav-

ing a wedge, e' , and a tongue, h , substantially as shown and described, to operate in the manner set forth, for the purpose specified. 15

2. The improved two-part buckle composed of the frame $a b' c d$, and the combined sliding and detachable wedge and loop, and guards $e e' f f' i i$, constructed in the manner shown 20 and described, for the purposes specified.

JAMES LALLY.
